(57) **CLAIM**

The ornamental design for a tool holder, as shown and described.

DESCRIPTION

FIG. 1 is an upper perspective view of the tool holder showing my new design.

FIG. 2 is a front elevation view thereof;

FIG. 3 is back elevation view thereof;

FIG. 4 is a side elevation view thereof;

FIG. 5 is an opposite side elevation view thereof;

FIG. 6 is a top plan view thereof;

FIG. 7 is a bottom plan view thereof;

FIG. 8 is a sectional view along the line 8-8 of FIG. 4; and,

FIG. 9 is an upper perspective view of the tool holder showing tools secured therein.

The features presented in broken lines are for environmental

purposes only and form no part of the claimed design.
